UNITED STATES PATENT OFFICE

2,161,093

RUBBER PACKAGE FABRICATION

Leroy L. Salfisberg, South Orange, N. J., assignor
to Ivers-Lee Company, Newark, N. J.; a cor-
poration of Delaware

Application November 21, 1936, Serial No. 112,112

1 Claim. (Cl. 206—56)

This invention pertains in general to container and package fabrications and specifically relates to such structures formed of rubber and the like.

One object of the invention is to provide a commodity package embodying novel and improved features of construction whereby the commodity shall be sealed within a moisture and air resistant material and the package can be easily and quickly opened for removal of the commodity.

10 Another object is to provide in such a package a novel and improved construction and combination of elastic transparent walls joined in an integral flange whereby the walls can be maintained under uniform tension around the commodity, and stresses in the walls shall be uniformly distributed.

15 A further object is to provide a package of this character wherein said walls and flange shall be constructed and related so that the flange shall 20 serve as a tearing tab to facilitate tearing of the walls of the package along the juncture of said walls and flange for opening the package.

25 These and other objects will be apparent from the following, reference being had to the accompanying drawing in which like reference numerals designate corresponding parts and in which:

Fig. 1 is a plan view of a preferred embodiment of a package structure in accordance with the invention; and

30 Fig. 2 is a sectional view taken along the line 2—2 of Fig. 1.

The invention contemplates providing an arrangement for packaging small articles in a unitary structure mounted in a single piece of chemically resistant moisture-impervious material. 35 This material is of a resilient non-fibrous composition which is adapted to produce a container structure closely fitting an enclosed article without producing strain or rupture in the packaging material. For example, articles with short or square corners can be packaged in accordance with the invention with packaging material stretched tightly over such corners without rupturing the packaging material or destroying its 40 moisture-proof qualities.

According to the invention, the commodity article is enclosed in a molded one-piece container embracing a flange structure adapted to encase the article with a minimum amount of the 45 packaging structure material while yet insuring facile opening characteristics. Referring to the drawing in detail, a commodity article 1 is enclosed between two walls 2 and 3 of a unitary container composed of transparent rubber. The rubber is of the treated type, having been prepared

in accordance with a known process to produce a transparent elastic stock suitable for the use described. The article 1, as shown in the drawing, is of rectangular configuration with square corners, although other shapes of articles can be 5 equally well packaged in accordance with the invention.

The walls 3 and 2 are drawn over the article 1 and meet in an encircling flange 4 disposed in a central plane of the article 1. It will be seen that 10 the walls 2 and 3 are stretched at points 5 and 6 where the walls are drawn over the edges of the article 1. However, this stretching is accommodated without rupture due to the elasticity of the composition of the walls 2 and 3. The flange 4 15 completely encircles the article 1 and, in accordance with the invention, is of a thickness substantially twice that of the walls 2 and 3. The flange 4 is therefore relatively stiff so as to reinforce the package, distribute stresses in the 20 walls 2 and 3 to maintain the walls under uniform tension and restrain warping or twisting of the package. The flange also provides a tearing tab to facilitate tearing of the walls 2 and 3 along the juncture of the flange with the walls to 25 enable the package to be easily and quickly opened.

The thickness d of either wall 2 and 3 is one-half the thickness of the flange 4. It will be seen that both the horizontal and vertical walls surrounding the article are closely adjacent to the surface of the article, and that there is very little waste space. This is made possible in this form of package structure by the configuration and composition of the material.

35 Referring to Fig. 1, the flange 4 is provided with opposed notches 7 and 8 on the outside edges thereof aligned with the inner surface of the vertical wall 9 of the casing structure extending between the horizontal walls 2 and 3. These 40 notches divide the encircling flange so that the right hand section 4a thereof, in effect, becomes a tab for tearing across the mouth of the container structure so that the contained article may be removed.

45 The formation of the package structure, molded around the commodity article in the form shown, is disclosed in the process described in my United States Patent No. 2,141,318 granted December 27, 1938. In accordance with this process, the transparent latex is simultaneously stretched and molded around the article to produce a close-fitting unitary structure in the form shown. After being molded, the package is allowed to cure for a predetermined time to insure the proper pack-

aging characteristics. Although a preferred form of rubber package fabrication has been disclosed, it will be recognized that various modifications and equivalent forms can be produced without departing from the intended scope of the invention. Therefore, no limitation is intended other than as is imposed by the appended claim.

What is claimed as new and original to be secured by Letters Patent of the United States is:

10 A package for a substantially rigid article, comprising a casing having thin walls of elastic rubber composition stretched around all sides of said article and being closely adjacent all surfaces of

the article, and an integrally joined molded flange surrounding the article in approximately a central plane thereof and being of substantial width and of a thickness substantially greater than the thickness of said walls, said flange being relatively stiff so as to reinforce the package, distribute stresses in said walls to maintain the walls under uniform tension and restrain warping or twisting of the walls and provide a tearing tab to facilitate tearing of said walls along the juncture of said flange with the walls to open the package.
